(57) **CLAIM**

We claim the ornamental design for a wall connector, as shown and described.

DESCRIPTION

FIG. 1 is a front perspective view of a wall connector; FIG. 2 is a front view of a wall connector of FIG. 1; FIG. 3 is a rear view of a wall connector of FIG. 1; FIG. 4 is a left side view of a wall connector of FIG. 1, the right side view is a mirror image of the left side view of FIG. 4; and, FIG. 5 is a bottom view of a wall connector of FIG. 1. The broken lines in the drawings depict environmental structure that forms no part of the claimed design.
